US00D994249S

(12) **United States Design Patent** (10) **Patent No.:** **US D994,249 S**
(45) **Date of Patent:** **** Aug. 1, 2023**

(54) **PET TOILET**

(71) Applicant: **Pingnan Zhengyuan Supply Chain Management Co., Ltd.**, Guangxi (CN)

(72) Inventor: **Yizhao Wei**, Guangdong (CN)

(73) Assignee: **Pingnan Zhengyuan Supply Chain Management Co., Ltd.**, Guigang (CN)

(**) Term: **15 Years**

(21) Appl. No.: **29/869,857**

(22) Filed: **Jan. 10, 2023**

(51) LOC (14) Cl. **30-11**

(52) U.S. Cl.

USPC **D30/161**

(58) **Field of Classification Search**
